UNITED STATES PATENT OFFICE

ALBERT E. EVANS, OF PITTSBURGH, PENNSYLVANIA, ASSIGNOR TO PITTSBURGH PLATE GLASS COMPANY, A CORPORATION OF PENNSYLVANIA

FLUID-COOLED ROLL

Application filed December 19, 1927. Serial No. 241,040.

The invention relates to fluid cooled rolls for use in glass rolling apparatus, such as that shown in the patent to Frederick Gels-tharp No. 1,560,079 of November 3, 1925, or the patent to Lee Showers No. 1,579,666 of April 6, 1926, although not limited to use in the particular apparatus of said patents. The invention has for its principal objects; the provision of a roll in which the tendency to warp under the severe heat conditions encountered, is reduced to a minimum; the provision of a roll, which is uniformly cooled by the fluid employed for that purpose; and the provision of a roll wherein the glass engaging portion may be readily renewed, either in part or in whole at a cost which is very small, as compared with the cost of the roll. One embodiment of the invention is illustrated in the accompanying drawings, 20 wherein:

Figure 1 is a longitudinal section through the roll. Fig. 2 illustrates the application of the roll in an apparatus such as that shown in the Showers patent referred to. Fig. 3 is 25 a partial end elevation and partial section on the line III—III of Fig. 1. Fig. 4 is a partial end elevation and partial section on the line IV—IV of Fig. 1. And Figs. 5 and 6 are sections on the lines V—V and VI—VI 30 of Fig. 1.

Fig. 2 illustrates the application of a roll to a rolling apparatus, the glass sheet 1 being formed between the rolls 2 and 3, the latter being the structure to which the present invention is directed. The rolls are suitably driven, the large roll 2 being supported from the inside by means of the rolls 4 and 5. The molten glass to be rolled into the sheet is supplied to the pocket 6 behind the rolls by 35 means of a melting pot or ladle and is rapidly rolled into a sheet which passes along the roller bed 7 into the leer where it is annealed. One of the difficulties encountered in a rolling operation of this kind is that of maintaining the roll 3 at a proper temperature. It must be adequately cooled and this cooling 40 should be uniform from one end of the roll to the other in order to avoid warping of the roll, as such warping introduces strains resulting in a rapid deterioration of the roll

and further produces a sheet which is not of uniform thickness. The present invention is designed to provide a cooling arrangement which will give the necessary uniformity in cooling and in which any warping is reduced to a minimum. 55

The roll 3 comprises the casing 8, preferably of cast iron, having the central portion cored out or counterbored to provide the chamber 9. Bearing portions 10, 10 are provided at the ends of the roll for supporting it in suitable journals. One end is provided with the driving member 11, to which the tumbler for rotating the roll is connected, such member being secured to the roll by means of the bolts 12. Suitably mounted on the member 11 are the swivels 13 and 14, the swivel 13 having an inlet 15, while the swivel 14 has an outlet 16. The swivel 13 is provided with passages which register with the 60 passages 17, 17a leading to the center of the roll, while the swivel 14 is provided with a passage registering with the passage 18, which latter communicates with the interior of the casing. At its other end, the roll is 65 provided with a cap member 19 held in place by the bolts 20 and carrying the three swivels 21, 22 and 23, the outer swivel being held in position by the member 24 which is secured to the cap 19 by the bolts 25. The swivels 21 and 70 22 are provided with inlet passages 26 and 27, whose inner ends register with the passages 28 and 29 leading to the central portion of the casing, while the swivel 23 is provided with an outlet 30 registering with the passage 31 leading to the interior of the casing. 75

Mounted upon the casing is a series of sleeves or collars 32, also preferably of cast iron or steel. These collars or sleeves are shrunk on to the casing 8 and are positioned with their ends closely adjacent, but out of actual contact. Additional securing means are provided for the end collars or sleeves in the form of the nuts 33 and 34, which are threaded upon the casing. The rolling surface made up of the collars 32 is not subject to warping to the same extent as a one-piece sleeve or casing, as the individual collars due to their separation can expand and contract longitudinally of the roll to a certain 80 85 90 95 100

extent without affecting the other members of the series. This arrangement has the further advantage that the series of collars may be removed and replaced when worn to such an extent that they are no longer serviceable, leaving the main portion of the roll intact for further service.

Water is circulated into the roll by means of the two sets of pipes 35 and 36 and 37 and 38, such sets of pipes being in concentric relation, as shown in Fig. 1, and having the closures 38 and 39, 40 and 41 at their inner ends, the closures 38 and 39 being provided with central outlet passages 42 and 43. These supply pipes are screw threaded into the members 11 and 19 at their inner ends, and are supported intermediate their ends by means of the studs 44 which are threaded at their inner ends into the walls of the pipes 37 and 38 and engage the inner walls of the casing at their outer ends. The spacing collars 45 also serve to support the inner pipes from the outer ones.

The inner pipes 35 and 36 are supplied with cooling fluid, such as water from the passages 28 and 17, respectively, while the outer pipes 37 and 38 are supplied with water from the passages 29 and 17a. The water supplied to the pipes 35 and 36 flows to the outer end thereof and is distributed through the perforations 46, some of it also passing through the openings 42 and 43. The water supplied between the pipes 35 and 37, and 36 and 38 flows outwardly through the walls of the pipes 37 and 38 through the perforations 47. The water thus supplied to the interior of the casing 9 flows outwardly to the ends of the casing, as indicated by the arrows in Fig. 1, and is discharged through the outlets 16 and 30. This arrangement gives an adequate circulation of the cooling water through the casing and distributes it so that the casing is cooled very uniformly.

What I claim is:

1. In combination in a roll, a cylindrical casing, a liquid supply pipe extending inward from each end of the casing, and discharging at its inner end, a second pipe also extending inward from each end of the casing surrounding the supply pipe and concentric therewith, receiving the discharge from the supply pipe and provided with a series of perforations at its inner end, means for supplying a cooling fluid under pressure to the outer end of each supply pipe, and means for withdrawing the fluid from the outer ends of the casing.

2. In combination in a roll, a cylindrical casing, a liquid supply pipe extending inward from each end of the casing, and discharging at its inner end, a second pipe also extending inward from each end of the casing surrounding the supply pipe and concentric therewith, receiving the discharge from the supply pipe and provided with a series of

perforations at its inner end, means for supplying a cooling fluid under pressure to the outer end of each supply pipe, means for withdrawing the fluid from the outer ends of the casing, means for supporting each of said second pipes intermediate its ends from the casing, and means for supporting each of said supply pipes from one of said second pipes.

3. In combination in a roll, a cylindrical casing, a liquid supply pipe extending inward from each end of the casing, and discharging through its inner end and also through its side walls at such inner end, a second pipe also extending inward from each end of the casing surrounding the supply pipe and concentric therewith receiving the discharge from the side walls of the discharge pipe, and provided with a series of perforations at its inner end, means for supplying a cooling fluid under pressure to the outer end of each supply pipe, and means for withdrawing the fluid from the outer ends of the casing.

4. In combination in a roll, a cylindrical casing, means for circulating a cooling fluid through the casing, and a jacket mounted on said casing and comprising a plurality of sleeves or collars shrunk on the casing and placed end to end, with such ends closely adjacent to each other but out of contact.

In testimony whereof, I have hereunto subscribed my name this 13th day of December, 1927.
